MOPHEAD FASTENER

Clement V. Martin, Dayton, Ohio

Application December 13, 1934, Serial No. 757,390

4 Claims. (Cl. 15—153)

This invention aims to provide a simple means for gripping the head of a mop, and holding the head of the mop together, without stitching, the device being capable of ready assembly with, and 5 ready removal from, mop holders of standard and approved constructions.

It is within the province of the disclosure to improve generally, and to enhance the utility of, devices of that type, to which the invention app-10 pertains.

The drawing shows, and this specification de-15 scribes, a satisfactory material embodiment of the invention, but it is to be understood that a mechanic, working within the scope of what is claimed, may make such changes as his skill may dictate, without departing in corresponding 15 measure from the spirit of the invention.

The reader is requested to consider the following specification in connection with the drawing, 20 wherein:

Fig. 1 is an elevation showing a mop holder wherein the claimed device is embodied;

Fig. 2 is a fragmental elevation, with parts broken away and parts in section;

Fig. 3 is a top plan of the clamp, with the mop head broken away;

Fig. 4 is a section on the line 4—4 of Fig. 2;

Fig. 5 is a side elevation showing the jaws, in the position which they will assume prior to 30 assembly with the mop head.

The device forming the subject matter of this application embodies a clamp, made up of two trough-shaped metal jaws 1, which are of identical construction, it being unnecessary, there-35 fore, to form two jaws which are different, a single form of jaw being sufficient, and the cost of manufacture being reduced accordingly.

The convexed sides 2 of the jaws 1 are disposed 40 toward each other. From each jaw 1, a bendable prong 3 is struck. Each jaw 1 has an opening 4. The prong 3 and the opening 4 are spaced apart, lengthwise of the jaws 1, and are located 45 at equal distances from the ends of the jaws, so that, when the jaws are turned end for end, as shown in the drawing, the prong will be in a position to pass through the hole 4 of the other jaw.

Each jaw 1 has a bendable tongue 5 at one 50 end, and when the jaws are reversed, end for end, as aforesaid, one tongue 5 is disposed at each end of the clamp. The tongue 5 of each jaw is bent into U-shape, to engage in the concavity 6 of the other jaw, at the end thereof.

The prong 3 of each jaw 1 is extended through 55 the opening 4 of the other jaw, and is bent to

engage said other jaw, in the concavity thereof. The jaws 1 may be connected intermediate their ends by a rivet 16. Some prefer to omit the prongs 3 and rely on the rivet 16. Some omit the rivet and use the prongs. There is no reason why both the prongs 3 and the rivet should not be used, if that course seems desirable. 5

The structure above defined causes the jaws 1 to grip the mop head 7 tightly and firmly, the jaws being made of sheet metal of sufficient thickness or strength so that they are rigid and substantial. Not only do the jaws 1 grip the mop head under pressure, but, as well, there is provided a positive means for preventing the mop head from slipping lengthwise of the jaws. That means embodies the rivet 16 and the prongs 3, which pass through the mop head, together with the tongues 5, which close the clamp at its ends. 10

The jaws 1 hold the mop head securely against slipping in any direction, and do away with the stitching generally required to keep the yarn of the mop head 7 together. Because the mop head 7 is not stitched or fastened together otherwise, the head can be opened out readily, when not in use, and will dry more quickly than is the case 15 when the head is stitched together into a more or less compact body. Since the mop head 7 can be dried thoroughly, it will last a long time. 25

The device can be used in any standard mop holder, such as the holder H, wherein the handle 30 8 is secured to one end of a loop-shaped frame 9, including side bars 10 and a foot piece 11. A slide 12 is mounted to reciprocate for adjustment on the side bars 10, and is under the control of an operating and pressure member, such as a 35 screw 14, threaded into the base of the frame 9. The clamp that holds the mop head 7 is bound between the foot piece 11 and the end 15 of the slide 12, the concavity 6 of one jaw receiving the foot piece 11 closely, and the concavity of the other jaw receiving the end 15 of the slide. 40

It is probably unnecessary to point out that the device for gripping the mop head 7 is strong, inexpensive to manufacture, easily assembled with a holder, such as the holder H, and easily 45 removed from the holder.

Having thus described the invention, what is claimed is:

1. A mop head clamp made up of two like, trough-shaped jaws, with their convexed sides 50 disposed toward each other, each jaw having a bendable prong struck from it, and each jaw having an opening, the prong and the opening being spaced apart lengthwise of the jaws, and being located at equal distances from the ends 55

- of the jaws, each jaw having a bendable tongue at one end, the jaws being reversed, end for end, to arrange one tongue at each end of the clamp, the tongue of each jaw being disposed in U-shape, 5 to engage in the concavity of the other jaw, at the end thereof, the prong of each jaw being extended through the opening of the other jaw and being engaged with said other jaw, in the concavity thereof.
- 10 2. The mop head clamp of claim 1, wherein the jaws are connected, additionally to the prongs, by a securing device disposed between the prongs.
- 15 3. A mop head clamp made up of two like, trough-shaped jaws, with their convexed sides disposed toward each other, each jaw having a bendable tongue at one end, the jaws being reversed, end for end, to arrange one tongue at each end of the clamp, the tongue of each jaw

being disposed in U-shape, to engage in the concavity of the other jaw, at the end thereof.

4. In a device of the class described, a mop comprising a frame including a foot piece, a slide mounted to move on the frame, toward and away from the foot piece, means for moving the slide toward the foot piece in clamping relation thereto, a mop head, trough-shaped members having their convexed portions disposed toward the mop head, the trough-shaped members being located on opposite sides of the mop head, and means for holding the trough-shaped members together, to cause them to bind upon the mop head, the concavity of one of the trough-shaped members being shaped throughout its length to receive the 10 slide, and the concavity of the other of the trough-shaped members being shaped throughout its length to receive the foot piece.

CLEMENT V. MARTIN.
